UNITED STATES PATENT OFFICE

DAVID WATSON TAYLOR, OF THE UNITED STATES NAVY.

SCREW-PROPELLER.

978,677.

Specification of Letters Patent.

Patented Dec. 13, 1910.

Application filed September 10, 1909. Serial No. 517,179.

To all whom it may concern:

Be it known that I, DAVID WATSON TAYLOR, a citizen of the United States of America, of the U. S. Navy, have invented certain new and useful Improvements in Screw-Proellers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to screw propellers, and has for its object a structure of the blade for these propellers to avoid the harmful effects due to cavitation. This I accomplish by a novel structure of the blades of the propellers and particularly of what is known as the backs of the propeller blades, the specific structure herein shown and described being at the leading portions of the backs.

Referring to the drawings, in which like parts are similarly designated, Figures 1 to 4 are sectional diagrams illustrating cavitation, and are herein shown to more clearly illustrate the reason for the new structure of blade embodied in my invention. Figs. 5 and 6 are developed sections illustrating well constructed blades of accepted type now in use, with the cavitation areas in relation thereto. Fig. 7 is a view similar to Fig. 6, of a blade embodying my invention. Fig. 8 is a similar view of a modification. Fig. 9 is a section corresponding to Fig. 8, showing strengthening ribs on the back for the thin leading edge. Fig. 10 is a section on line 10-10 of Fig. 9. Fig. 11 is a developed outline of an ogival blade showing the back thereof and a developed section of a serrated edge reinforced by ribs.

A full understanding of the invention will be facilitated by a brief description of cavitation and its causes, reference being had to Figs. 1-6 of the drawings.

In Fig. 1 is shown a small circular cylinder 2 which is supposed to be immersed in water that is flowing past it from left to right, the lines indicating lines of flow. If the velocity of the water is great enough it will not flow smoothly around this cylinder, but will part at the front of the cylinder and come together again behind it at some

point, as *a*, leaving behind the cylinder a substantially vacuous space, as shown at *b*. If, instead of the cylinder 2 being at rest and the water flowing past it, we move the cylinder with sufficient speed through water at rest, we shall have the same cavitation.

In Fig. 2 there is attached to the cylinder a portion 3 of a propeller blade which lies wholly within the cavity *b*. It is evident that this blade 3 would have no propulsive action, and that if an actual screw propeller blade were made up of a cylinder in front, and a blade of the ordinary ogival section, it would have no propulsive action if it were rotated at such a speed that the main body or ogival section was always in the cavity formed by the motion through the water of the cylindrical portion constituting the leading edge. Propellers are not made with their leading edges sections of cylinders, as shown in Fig. 2, but they are frequently made with their leading edges 4^a rounded, as illustrated by the developed blade section 4, shown in Fig. 3. A screw-propeller blade having a rounded leading edge, such as shown in Fig. 3 will, if driven through the water at a sufficiently high speed, inevitably produce cavities not only at the back of the blade, as indicated at *c*, but also in front of it, as indicated at *d*, over the driving face of the blade. These cavities or partial vacua over the face of the blade, where there should be the maximum pressures, are fatal to efficiency. When considering these matters we should remember that cavitation troubles appear when the actual velocities of propeller blades through the water are very high, 10,000 feet a minute and more, or over a hundred miles an hour. Under these conditions a very small round at the leading edge of a propeller blade will produce large cavities. It is an improvement in propeller blade construction to make the blades with leading edges that are not rounded as shown in Fig. 3, but sharp, but when the speed of the propeller through the water becomes exceedingly great, this construction fails with blades having sections hitherto used, for reasons which I shall now explain.

In Fig. 4 I have shown a developed section of an ideal propeller blade, 5-6, of no thickness advancing through the water in a direction *e-f*. Here the angle 5, *e*, *f* is

what is known as the "slip angle." At some point g on the face of the blade the water in front of the face parts, a portion flowing around the leading edge at 5 to the back of the blade, and the rest flowing along the face of the blade toward 6 . No matter how small the slip angle, and in practice it is a very small angle, the point g will not reach the leading edge 5 , as long as the slip angle 10 has a value, and there will be no defect of pressure on the face of the blade. So while the ideal blade $5-6$ of no thickness would show no cavitation over the face of the blade, it will show it over the back of the 15 blade.

Now let us consider what happens to the actual blade: In Fig. 5 I have shown an actual blade section 7 advancing with a slip angle of 3° , which is a reasonable slip angle value, especially for screw-propellers of fine pitch; but the angle between the face and back of the blade at the leading edge 5^a 20 is 25° . Hence, while the water strikes the face of the blade at an angle of 3° , it strikes the leading portion of the back of the blade 25 at 22° . The back overpowers the face, by reason of the water parting at some point on the leading portion of the back, as h , and flowing around the leading edge, producing cavitation over the face of the blade, as indicated at i . This cavitation on the face of the blade is fatal to efficiency. It is true that the water flowing around the curved back of the blade will, if the speed be great 30 enough, fail to follow it, and cavities, as indicated at k , will be formed at the back of the blade, but these cavities contribute thrust unless they fill with air drawn from the air occluded in the water. If they were 35 complete vacua there would be very little objection to them, and even if they are only partial vacua they do not reduce efficiency nearly as much as partial vacua on the face. It is not a difficult matter to avoid a construction 40 that causes a flow from back to front, as in 45 Fig. 5.

In Fig. 6 the face of the blade is rounded on its forward portion and the back is made tangent to the line of advance. In this case 50 the water parts at some point, as l , on the face, and flows from face to back, as in the ideal blade of no thickness. There is no cavitation at the leading portion of the blade face; but, as the blade face is rounded, 55 if the speed is high enough, the water is thrown off from this rounded portion, resulting in cavitation over the face of the propeller blade some distance back of the leading edge, as indicated at m , Fig. 6.

60 It is evident from my discussion as above stated, that if the angle of the blade, between surfaces of the face and back of the blade, at the leading edge is less than the slip angle, face cavitation can be wholly 65 avoided. With the usual ogival sections

this is not possible with actual blade thicknesses, as slip angles are too small to give the thickness of blade required for strength. With ogival sections the wider the blade, the smaller the blade angle at the leading 70 edge, and this is the reason for the recognized value of wide thin blades of the usual ogival section for preventing cavitation. Such blades, however, are objectionable from many points of view, and if forced to 75 speeds sufficiently great will cavitate, and it is desirable to construct a blade that will absolutely prevent cavitation on the face, without the use of blades that are excessively wide or excessively thin. This I accomplish by means of blades in whose developed section the face is straight or nearly straight and whose back is hollow along the leading portion thereof adjacent the leading edge. The developed section of such a blade made 80 85 in accordance with my invention is shown in Figs. 7 to 11.

The blade angle at the leading edge forms, preferably, a sharp knife edge, as at 7 , Fig. 7, and this angle is preferably not made 90 greater than the slip angle, though it is hardly practicable to make it less than three degrees. By making the propeller blade hollow, *i.e.*, with reducing or decreasing pitch at the leading portion of the back of the 95 blade, as at 10 , and 10^a , Figs. 7 and 8, this sharp edge can be employed without reducing the strength of the blade below practicable limits.

With my improved structure of propeller 100 blade as shown in the developed section thereof, Fig. 7, the water will part at some point on the face, as indicated at n , and flow around to the back of the blade by way of the leading edge 7 , as in the ideal blade Fig. 105 4, and there will be substantially no cavitation on the face of the blade. There will be cavitation at the back of the blade, but if the cavities are perfect vacua they will be helpful rather than harmful on the back, 110 and if they are not high vacua the air can be exhausted from them as described in my Patent No. 900,797.

With a propeller blade having a hollow back adjacent to the leading edge a straight 115 or nearly straight face and an edge angle not greater than the slip angle, as shown in the developed section, Fig. 7, the cavitation over the face of the blade (a phenomenon which though not hitherto recognized, I 120 have found to exist, and to be the chief cause of the reduction of efficiency accompanying cavitation) cannot occur any more than in the case of the ideal blade of no thickness.

125 While my novel type of hollow backed blade is particularly valuable for preventing cavitation over the blade face it is a structure of propeller blade of superior value for propellers operating under conditions 130

where cavitation is not to be feared. This, for the reason that with such a construction of blade there is in practice over the whole blade back suction which assists the thrust that is due to the face action; while with the usual ogival section of blade, the same conditions that produce cavitation when the propeller is hard driven will below cavitating speeds produce a backward thrust over the leading portion of the face of the blade, which is very detrimental to efficiency.

It is not necessary that the hollow back should be one continuous curved surface, and in Fig. 8, I have shown a developed section of a relatively thick propeller blade 11, whose face is extended by a thin sharp blade 12 secured to the face of the propeller blade at the leading portion thereof, said plate 12 forming a dis-continuous curve between its back and the back of the propeller blade 11 proper, to form the hollow 10° of the hollow back.

To secure greater strength when it is necessary to make the leading portion of the propeller blade extremely thin, especially in blades whose hollow backs are formed in a continuous curved surface at these leading portions, I secure to or form integral with the backs of such blades, ribs 13, Figs. 9 and 10.

Fig. 9 is a section identical with Fig. 7 showing the rib 13 formed thereon. The ribs are preferably placed short distances apart as shown in Fig. 11 and these ribs are preferably perpendicular to the back of the blade and at their roots they merge in beveled or curved surfaces 14 into the surface of the back. The leading ends of these ribs are inclined to the back as indicated at 15, Fig. 11 and are beveled or sharpened. The following portions of these ribs merge into the back of the blade.

In Fig. 11 I have illustrated such a hollow backed blade, relatively thin, having ribs 13 sharpened at their leading ends 15 and the leading edge of the blade is serrated, there being a rib extending to the point of each tooth 16 of the serrated leading edge. The ribs of Fig. 11 may be omitted and the serrations will enable the use of slightly blunter blades but when a rib 13 is run on the back of the propeller blade to the point of each tooth 16 there results a construction of superior strength.

The essential feature of my invention is the hollow or concave back extending from the leading edge and preferably merged into the customary curved or convex back, serrated or not serrated, at the leading edge and supported or not supported by ribs. This hollow back may be combined with a face of any usual type but for the best results to avoid cavitation at the most extreme speeds, I prefer that the face be a true helicoid of uniform pitch, showing as a straight

line in the developed sections Figs. 2, 3, 4, 5, 7, 8, 9 and 11 or it may be slightly rounded toward the leading edge.

I claim:

1. A rigid propeller blade having in its developed section a substantially straight face and a curved back having a hollow formed therein adjacent a leading sharp edge.

2. A rigid propeller blade having in its developed section a substantially straight face and a curved back of decreasing pitch adjacent the leading edge.

3. A screw propeller blade having the angle between the face and back of the blade at each point of the leading edge substantially equal to the angle of slip and the back of the blade adjacent the leading edge of decreasing pitch.

4. A rigid propeller blade having in its developed section a substantially straight face extending to a sharpened leading edge, and a curved back meeting the bevel on the back of the blade that forms said sharp leading edge.

5. A propeller blade having in its developed section a substantially straight face extending to a sharp leading edge, and a back formed by a compound curve concave to the face in the immediate vicinity of the leading edge, and convex over the major portion of the back.

6. A screw propeller blade having its back concave and a continuous curved surface, adjacent the leading edge, the leading edge 100 serrated and ribs on the back of the blade extending from the serrations to the body of the blade and concentric with the center of rotation of the blade.

7. A screw propeller blade having the angle between the face and back of the blade at each point of the leading edge substantially equal to the angle of slip, the back of the blade adjacent the leading edge of decreasing pitch and the leading edge serrated.

8. A screw propeller blade having a hollow formed in the back of the blade along and adjacent the leading edge, the leading edge serrated and ribs extending from the serrations to the body of the blade.

9. A propeller blade having in its developed section a substantially straight face extending to a sharp leading edge, and a back formed by a compound curve concave to the face in the immediate vicinity of the leading edge and convex over the major portion of the back, and ribs, concentric with the axis of rotation of the blade only on the leading portion of the back of the blade.

10. A screw propeller blade having the angle between the face and back of the blade at each point of the leading edge substantially equal to the angle of slip, the back of the blade adjacent the leading edge of de-

creasing pitch, and strengthening ribs on the back of the blade.

11. A screw propeller blade having the angle between the face and back of the blade at each point of the leading edge substantially equal to the angle of slip, the back of the blade adjacent the leading edge of decreasing pitch and strengthening ribs on the back of the blade extending from the leading edge toward the center of the blade and merging into its back.

12. A screw propeller blade having the angle between the face and back of the blade at each point of the leading edge substantially equal to the angle of slip, the back of the blade adjacent the leading edge of decreasing pitch and strengthening ribs on the back of the blade extending from the leading edge toward the center of the blade and merging into its back, said ribs beveled or sharpened at their leading ends.

13. A screw propeller blade having a hollow back adjacent the leading edge, the

leading edge serrated and ribs on the back of the blade extending from the point of each serration to and merging into the back.

14. A propeller blade having a plate secured to and projecting beyond the body of the blade to form a thin leading edge, the angle between the front and back surfaces of said plate being substantially equal to the angle of slip.

15. A rigid propeller blade having the back of the blade adjacent the leading edge of decreasing pitch and convex to the face of the blade over the major portion of the back and strengthening ribs extending from the leading edge on the leading portion of the back of the blade.

In testimony that I claim the foregoing as my invention, I have signed my name in presence of two subscribing witnesses.

DAVID WATSON TAYLOR.
